The ornamental design for a palm feed glue gun, as shown and described.

DESCRIPTION

FIG. 1 is a right side elevation view of a palm feed glue gun showing our new design. The left side elevation view is a mirror image thereof;

FIG. 2 is a front elevation view thereof;

FIG. 3 is a top plan view thereof;

FIG. 4 is a bottom plan view thereof; and,

FIG. 5 is a rear elevation view thereof.

The broken line showing is for illustrative purposes only and forms no part of the claimed design.
